APPARATUSES COMPRISING DIAPHRAGMS
 Etienne Rehacs, 56 Rue d'Eaubonne,
 St. Gratien, France
 Filed Feb. 27, 1962, Ser. No. 176,144
 Claims priority, application France Mar. 18, 1961
 5 Claims. (Cl. 200—83)

This invention relates to apparatuses comprising membranes or diaphragms, in which the deformation of the membrane under the action of a pressure is utilized either to measure the variations in pressure or to act as a function of these variations on a controlled member.

This deformation which is a function of the diameter, the nature of the metal and its thickness is, in consequence, restricted within very narrow limits, which causes restrictions in use, both as concerns the range, that is to say the interval between the limits between which the variations are used, and as concerns the working pressure, that is to say either the means value between the limits or the value of each of these limits.

According to a first improvement, a double-walled diaphragm is used as already known, but the shells, constituting the walls of the pressure chamber, are mounted to allow both shells free to respond to changes in pressure inside the pressure chamber.

According to a second improvement, the deformation is transmitted through an elastic member, the elasticity of which can be modified in the position of use, more particularly by a remote control.

One embodiment of the inventive idea will be given hereunder without its being intended to restrict the generic scope of the invention to the features given in the example selected for illustration.

In the accompanying drawings the invention has been shown as applied to the control of a contactor.

FIGURE 1 is a diagrammatic section through an apparatus according to the invention, and

FIGURE 2 is a section along the line 2—2 of FIGURE 1.

In the figures, 1 designates generally a casing which contains a contactor 2 as well as a diaphragm detector and its adjusting member.

The contactor is of any usual commercial type and therefore its design and functioning will not be described. It is controlled by a movable contactor part or push button 3.

It is for the control of this push button that the diaphragm detector, which is constituted as follows, is used:

In the upper part of the casing, designated more particularly by 4 and closed by a cap 5, is located the double diaphragm designated generally by 6 and constituted by two thin shells of steel, namely the lower shell 7 and upper shell 8; each of these shells has a peripheral flange so as to leave therebetween even in the position of rest, a space 9.

The upper shell has an extension 10 provided with a central bore 11 which opens into a connection 12 by means of which the source of pressure is connected.

The edges of the shells 7 and 8 are pressed firstly between a shoulder on a sleeve 13 and secondly between a nut 14 which is screwed by means of an internal thread into the sleeve 13. Between the two shells is located a packing 35 of rubber or similar material having a circular cross-section 35.

The sleeve 13 moves freely in the casing 4, in which it is simply supported by the extension 10, which is locked in a housing of corresponding form in the cap 5. The position of the lower shell 7 is marked by a push-rod 15 which passes by means of a sleeve through a wall 16, which forms the lower part of the casing 4.

2

It follows from the foregoing that under the effect of the pressure, the shells 7 and 8 constituting the double shell may assume a lenticular form, each diaphragm having a semi-lenticular form. The result of this is that the displacement is double what can be obtained, all other things being equal, with a single shell.

Instead of permitting the push rod 15 to bear directly on the push button 3, there is interposed between the push button and the push rod, a stirrup-member 17, at the base of which is inserted a rigid metal packing 38.

The stirrup member 17 is supported by a second stirrup member 18, the plane of the branches of which is perpendicular to the plane of the branches of the stirrup member 17, as seen in FIGURE 2.

The stirrup member 18 is held by journals 19 and 20 which may move inside two apertures 21 and 22 formed in the casing 1.

These journals are integral with sleeve 23 having an internal thread and through which passes threaded rod 24, which is terminated by head 25, which passes through the wall of the casing 1 and this head is held so as to prevent any longitudinal movement by plate 26 housed in the thickness of the wall of the casing.

The head 25 is provided on the outside with a slot, which enables the head to be turned by means of a screw driver, thus allowing the stirrup member 17 to be displaced with respect to the push rod 15.

As a result, if the stirrup member 17 is withdrawn to the extreme right, the push button 3 and the push rod 15 will bear on the flexible ends of the branches of the stirrup member and there will therefore be a considerable dead stroke before the action of the push rod 15 is transmitted to the push button 3. If on the other hand, the stirrup member 17 is pushed to the left, so that the push button 3 and the push rod 15 bear on the part of the branches enclosing the packing 38, the transmission of the action of the push rod 15 on the push button 3 will be instantaneous.

The action of the stirrup member 17 may be combined with another regulating device for allowing the push button 3 to be moved away from the stirrup member 17 to a greater or lesser extent.

To this end, the contactor 2, instead of resting on the bottom of the casing, is housed in a cradle 27, which is fixed to the body of the case 1 at two points 28 and 29 by riveting or by any other means. These two points determine an axis of rotation.

At the other end of the cradle 27, the latter bears on a nut 39, which is controlled by a screw 30, the head 31 of which is accessible from the outside. The head is immobilized inside the casing by plate 32.

One may therefore, either by acting on the head 25 or on the head 31, or by acting on both these heads, vary firstly the range of operation and secondly the working pressure.

What I claim is:

1. In a pressure responsive switch of the type including a movable contactor adapted to be moved to complete a circuit, a pressure chamber comprising a pair of shells each provided with a transversely extending peripheral flange extending toward the other with their free edges in mutual contact to thereby define a pressure chamber whereby both shells are free to respond to changes in pressure within the chamber, means for clamping the shells together comprising a pair of rings respectively abutting the outer surfaces of the shells about their marginal edges and having cooperating means for detachably securing them together to tightly clamp the flange edges against each other, a support, means at the center of one of the shells for freely suspending them and the attached clamping means from the support in fixed relation thereto, conduit means in said support whereby the inside of

said pressure chamber may be connected to a pressure source, and means operated by the other of the shells for transmitting movements thereof in response to changes of pressure in the chamber to said contactor.

2. In a pressure responsive switch as defined by claim 1 including an annular yieldable packing within the chamber extending along the internal surfaces of the flanges, whereby the packing is pressed towards said flanges in response to internal pressure within the chamber for sealing the shells along the line of mutual contact of the flanges.

3. In a pressure responsive switch as defined by claim 1 in which the clamping rings are provided with respective internal and external screw threads for detachably securing them together.

4. In a pressure responsive switch as defined by claim 1 in which the means for transmitting the movements of the other shell comprises an elongated flexible member extending transversely between the other shell and said movable contactor, means movably supporting the flexible member at one end thereof for transverse movement relative to the direction of displacement of said contactor, and means for shifting the support and flexible member longitudinally thereof.

5. In a pressure responsive switch as defined by claim 4, in which the flexible member is provided by a pair of flexible arms branching at their ends from the support means and extending in transversely spaced parallel relation, and a rigid packing between the arms adjacent to the support.
